LATCHING ASSEMBLY

August John Braun, Chicago, Ill.

Application March 10, 1951, Serial No. 214,982

1 Claim. (Cl. 292—113)

1

The present invention relates to a latch assembly and is more particularly concerned with a device of this type which is especially suitable for fastening cooperating edge portions of separable parts of a container structure, such as a closure or lid and a receptacle or casing having an opening adapted to be closed by said closure or lid.

According to the present invention a fixed abutment such as a hook on one of said parts is adapted to be engaged by a claw member hinged on a reversely-directed handle lever pivotally attached to the other of said parts, and the joint by which the claw member is hinged on the handle lever constitutes a toggle joint whereby when the claw member is in a position to engage the hook the toggle joint is rotatable away from the hook and beyond the position of dead center to cause the claw to forcibly engage the hook and thus form a secure fastening of the parts.

It is an important object of this invention to provide a latch assembly of the type described which is simple and efficient in operation and which is cheap to manufacture.

It is a further object of this invention to provide a latch assembly which is pleasing in appearance.

A still further object resides in the provision of a latch assembly arrangement wherein the elements thereof which straddle the cooperating edges of the parts of the structure carrying said latch mechanism are so confined when in unlocked condition and the parts of the structure are separated that said edges are free from overhang by said latch elements.

Other and more specific objects of this invention will appear from the description which follows:

In the drawings:

Fig. 1 is a top plan view showing fragmentary areas of separable parts of a typical structure with which the present latching assembly is adapted to function, said latching assembly being illustrated in a position to fasten said parts in locked position.

Fig. 2 is a side elevational view thereof, with the parts of the structure to which the latching assembly is applied being shown in section.

Fig. 3 is a vertical sectional view taken on line 3—3 of Fig. 1.

Fig. 4 is a similar view wherein the elements of the latching assembly are shown in full lines, and showing in dotted lines the relative position of said elements when the lever is positioned to locate the claw member over the hook.

2

Fig. 5 is a view, partly in section, taken on line 5—5 of Fig. 3, and partly in elevation.

Fig. 6 is a vertical sectional view, like Fig. 3, but showing a modified form of hook.

Referring, more particularly, to the drawings, separable parts 10 and 11, having cooperating edges, meeting as at 12, represent a typical structure, in connection with which a latching assembly embodying the features of this invention is adapted to be employed. A plate 13 fastened to the part 10 by screws, 14, or any other suitable fastening means, has an end portion away from the edges 12, which is bent upwardly at an acute angle relative to the surface of the part 10 to form a hook 15. A bracket or attachment plate 16 fixed by screws, or the like, 17 on the part 11 of said container structure is provided with trunnions 18 on which a lever 19 is mounted for swinging movement toward and away from the cooperating edges 12 of the parts 10 and 11. As shown in Fig. 4, the lever 19 is thus adapted to rotate about the trunnions 18 as a pivot between a depressed position and a raised position relative to the surface of the part 11.

The claw member comprises a housing 20 having spaced apart sides 21 connected at one edge by a cross-web 22. Corresponding sides 23 on the handle lever 17 are straddled by ears forming extensions of the sides 21 of the claw member in a direction away from the cross-web 22 and a transverse bearing pin or shaft 24 extending through aligned openings in said ears on the claw member and the sides of the handle lever 17 overlapped thereby provides a pivot or axis about which the claw member is rotatable relative to the handle lever 17 parallel to the axis of movement of the latter about the trunnions 18. The transverse edge 25 of the claw member away from the cross-web 22 presents an abutment engageable by the surface of the handle lever 17 opposite thereto to limit movement of the latter in the direction of the cooperating edges 18 and 19.

As shown in dotted lines of Fig. 4, wherein the handle lever 17 is thus shown in a depressed position, the pivot 24 is located above a line A—A through the pivot 16 of the handle lever 17 and the hook 10, and the claw member is situated over the hook in readiness for engagement with the hook 10 or for movement of the claw member in unison with the rotation of the handle lever 17 to the full-line position. The interfacing surfaces of the sides 21 of the claw member and the sides of the handle lever 17 about the pivot 24 have such binding engagement therebetween as to releasably hold the claw member and handle

lever in selected relatively rotated positions when the claw member is disengaged from the hook 15.

Upon rotating the handle lever 17 to the raised position as shown in dotted lines in Fig. 4, the claw member is accordingly restored to a position wherein the cross-web 22 is again in readiness to engage the hook 15, whereupon by downward pressure applied manually against the claw member of sufficient force to overcome the binding relation of the latter relative to the handle lever 17 about the pivot 24 accompanied by similar pressure against the handle lever 17 the latter in returning to its position at the limit of movement away from the claw member acts through the pivot 24 to draw the claw member toward the handle lever with the result that the cross-web 22 is pressed into firm engagement with the hook 15. Due to the movement of the pivot 24 across the imaginary line A—A to a position below the latter in accordance with such rotation of the handle lever in a direction away from the hook 10, the pivot 24 serves as a toggle joint which prevents unlocking movement of the parts until the lever is returned to an erect position to break the toggle joint.

The transverse edge of the handle lever 17 facing away from the claw member is preferably arranged to occupy a position in spaced relation to the surface of the part 11 when in a collapsed position and the handle is relatively close thereto as shown in Fig. 3, so as to provide a comfortable finger gripping surface for moving the lever 17 into an erect position. This edge is also curled inwardly in the form of a hollow bead 26 on the underside of the lever 17. A spring member 27 having one end crimped within said bead and its opposite end portion bearing against a notch 28 in the edge of the attaching plate or bracket 13 between the trunnions 16, is secured under tension against the underface of the handle lever 17 whereby the latter is yieldably biased into a depressed position as shown in Fig. 3. Accordingly the spring member 27 provides means through which the handle lever 17 and the claw member are normally rotated into a position away from the meeting edges 12 of the structure with which the latching assembly cooperates, so as to leave said edges free from overhang by the claw member when the latter is disengaged from the hook 10.

Fig. 6 illustrates a modified form of hook 29 which is formed as part of an integral abutment with the body of a structure 30 in connection with which a handle lever 17 and claw member as described in connection with the latch assem-

bly shown in Figs. 1 to 5 inclusive is similarly operative to fasten the cooperating edges of the structure 30 and a part 31.

It will be noted that the claw member in either form of hook shown in Figs. 1 to 5 inclusive or Fig. 6 provides a housing adapted to conceal the hook from view when the claw member is in locked engagement therewith. Thus the appearance of the latch assembly contemplated by this invention is a feature of improvement over latch assembly arrangements heretofore in use.

It will be understood that numerous modifications and rearrangements of structure may be made from that illustrated without departing from the spirit of the invention as set forth in the following claim.

What is claimed is:

A latch assembly for fastening cooperating edge portions of separable parts of a structure comprising a hook secured on one of said parts facing away from said edge portions, a bracket secured to the other of said parts having an extension in the direction of said edge portions provided with integral trunnions spaced apart lengthwise of said edge portions, a lever supported on said trunnions for swinging movement between raised and depressed positions relative to said bracket, a member supported on the lever for swinging movement about an axis which axis is offset from the dead center line intersecting the hook and the trunnions so that movement of the lever between raised and depressed positions causes said axis to be shifted across said dead center line, said member being adapted to be moved into a position over said hook when the lever is in raised position, hook engaging means on the member with which the hook cooperates to lock said parts in fixed relation by movement of the lever from raised position to depressed position while the member is positioned over the lock, said lever having a hollow bead formed at the underside of its swinging end which bead faces the trunnions, and a spring member having one end trapped within said bead and its opposite end portion bearing on the edge of the bracket between said trunnions operative to yieldably bias said lever into a depressed position.
